UNITED STATES PATENT OFFICE.

JOHN W. LUFKIN, OF BOSTON, MASSACHUSETTS.

AUTOMATIC BUTTONHOLE CUTTING AND STITCHING MACHINE.

SPECIFICATION forming part of Letters Patent No. 678,825, dated July 16, 1901.

Application filed March 12, 1901. Serial No. 50,950. (No model.)

To all whom it may concern:

Be it known that I, JOHN W. LUFKIN, a citizen of the United States, residing at Boston, in the county of Suffolk and State of Massachusetts, have invented certain new and useful Improvements in Automatic Buttonhole Cutting and Stitching Machines, of which the following is a specification, reference being had therein to the accompanying drawings.

10 Figure 1 is a front side elevation of my improved machine. Fig. 1^a is a detail, partly in section, at line 1^a 1^a of Fig. 1 of interlacer mechanism. Fig. 2 is a top plan view of the machine. Fig. 3 is an under plan view of the 15 machine-bed and working parts carried or supported on the under side of the bed. Fig. 4 is a perspective view of the machine when the bed is tipped up and back on its supporting-bracket, a portion of the bracket being 20 broken away. Fig. 5 is a top plan of the bed of the machine and of sundry working parts supported by the bed, the gooseneck of the machine being removed for greater clearness. Fig. 6 is a front end elevation of the machine 25 with the front plate removed. Fig. 7 is a sectional view on a line corresponding to 7 7 of Fig. 5, but showing the detail of the clamping and other mechanism not shown in Fig. 5. Fig. 8 is in part an enlarged sectional 30 detail of the parts shown in the upper right-hand portion of Fig. 7, but shows the clamping-lever and starting-pawl connected therewith in full lines. Fig. 9 shows in edge view and also partly in section a detail of the 35 thread-tension plate. Fig. 10 is a rear elevation of the machine. Fig. 11 is a section on line 11 11 of Fig. 5 and shows details of the stitching-starting shaft. Fig. 12 is an end view of the worm-gear loose on the stitching- 40 starting shaft and shows the pin-receiving recesses, with which one end of the worm-gear is provided. In this view the pin, which is projected from a pin-carrier fast on said shaft into one of said holes, is shown in section. Fig. 12^a is mainly a lengthwise section of sundry working parts carried by the bed of the machine, showing also, partly in section and partly in elevation, co-operating parts above the parts carried by the bed. This view shows 45 the stitching-starting shaft and its connections with the stitching mechanism, the understitching-shaft, some of the gears which

turn the turn-table, and various other parts. The view in so far as it is a section is taken at a line corresponding to line 12^a 12^a of Fig. 5 and also shows in section the cutter-anvil and interlacer. Fig. 13 is a view, partly in section, at line 13 13 of Fig. 5 and shows a detail of the under cutter-lever and its connection with the triangular cam on the stitching-starting shaft. Fig. 14 is a sectional view at line 14 14 of Fig. 5 and shows the loose worm-gear on the stitching-starting shaft engaged by the worm of the auxiliary shaft, by which the stitching-starting shaft is preferably driven. Fig. 15 is a view, partly in section, at line 15 15 of Fig. 5 and shows a detail of the work-clamp-locking mechanism. Fig. 16 is a view, partly in section, at line 16 16 of Fig. 3 and shows the construction of the worm with which the under driving-shaft of the machine is provided in order to vary the speed of the feed-wheel during the formation of each stitch. Fig. 17 is a top plan view of the turn-table, clamp, and spreading mechanism carried thereby. Fig. 18 is a plan view of a plate having a groove which controls the movements of the feed-pin, which passes from the turn-table through said guide-groove into a cam-groove in the feed-wheel underneath 80 said plate. Fig. 19 is a view, partly in section, at line 19 19 of Fig. 5 and shows details of the mechanism which actuates the turn-table. Fig. 20 is a side elevation, with spring attached, of the stop-lever which stops the machine at the completion of each buttonhole. Fig. 21 is a side elevation of a three-armed lever which is loosely mounted on the stitching-starting shaft and is instrumental in stopping the machine at the end of the stitching 85 of each buttonhole, in releasing the thread-tension-opening lever, and in disengaging the connection between the stitching-starting shaft and the actuating mechanism of the under driving-shaft. Fig. 22 is an edge view 90 of the lever shown in Fig. 21. Fig. 23 is a perspective view of the rocker-shaft for locking the feed-wheel and stitching mechanism during the cutting of the buttonhole. Figs. 24 and 25 are views of the incline levers for 95 unlocking the turn-table after the buttonhole is cut. Figs. 26 and 27 are different views of the worm-gear driven from the under cutter-shaft, Fig. 26 being partly in section, so as to 100

show the locking-stud with which it is provided. Fig. 28 is a central sectional view on line 28-28 of Fig. 26 and shows the locking-stud in its place in the worm. Fig. 29 shows in plan and section, at line $\alpha\alpha$ of the plan, my new buttonhole in which the threads are superimposed at the small end of the buttonhole, the last stitch being in the same hole as the first stitch. Fig. 30 is an enlarged view illustrating the stitch made by my present machine, this stitch being that of the method of my United States Letters Patent No. 461,841 and this figure corresponding to Fig. 1 of that patent. Figs. 31 to 39 are views showing the concatenation of the threads at different stages of the formation of the stitch and showing also stitching instrumentalities in different operating positions. Fig. 31 shows the two threads through the upper needles and extending through the needle-holes of the throat-plate. Fig. 32 shows the threads interlaced around the needle which passes through the buttonhole-slit. Fig. 33 shows both needles through the throat-plate in position to form loops for the under thread. Fig. 34 shows the under needle or looper with its under locking-thread passed through the loops of the upper threads. Fig. 35 shows the upper needles in a rising position and shows the under thread passed through the upper-thread loops and placed on the spreader. Fig. 36 shows the spreader placing its loop in position for the reception of the needle which passes through the buttonhole-slit. Fig. 37 shows the descent of the upper needles in forming the next stitch, the center needle, the one which passes through the buttonhole-slit, passing through the loop in the under thread which is held open on the spreader. Fig. 38 shows the under-thread-cutting knife cutting the under thread off after the last stitch of the buttonhole is made while the under thread is still held on the spreader. Fig. 39 shows the position of the under thread as it is passed through the upper-thread loops, the cut end of the under thread being left extended through the upper-thread loops to prevent the final stitch from becoming loosened or ripping out. Fig. 40 is a side elevation of the work-clamp, showing the work-clamp lever lifted. Fig. 41 is a perspective showing mechanism whereby the work-clamp is connected with the under cutter-lever. Fig. 42 is a top plan of the thread-cutter removed.

The objects of my invention are to simplify the mechanical construction of automatic buttonhole cutting and stitching machines and to produce an automatic buttonhole cutting and stitching machine that will be capable of producing a greater number of completed buttonholes in a given length of time than has been possible heretofore. It is to be understood, however, that the actual product of machines of this class is dependent in a large measure on the skill and attention of the operators because the material to be cut

and stitched has to be moved manually in the work-clamp after the completion of each buttonhole, these machines being automatic only in respect of the cutting and stitching of each buttonhole, separately considered.

Another object of my present invention is to produce the new kind of buttonhole hereinafter described according to the method of forming buttonhole-strokes patented in my United States Letters Patent No. 461,841, of October 27, 1891. My present machine is the first one I have been able to devise for carrying out in a highly successful manner the said patented method.

A brief reference to the prior art will assist in understanding the nature and scope of my invention.

In numerous Letters Patent of the United States, among which are No. 50,253 to Humphrey, of October 3, 1865, No. 78,821 to Peabody, of June 9, 1868, and No. 115,163 to Chicken, of May 23, 1871, there is disclosed a type of buttonhole-stitching machine mechanical characteristics of which are, first, a clamping and spreading mechanism carried by a turn-table, and, second, a turning of the turn-table between upper and under stitch forming devices to present successive portions of the margin of the buttonhole-slit to the stitching instrumentalities. The work-clamp in this style of machine, which was long known as the "Union," not only clamped the work, but gave an initial movement to the fabric by pulling the opposite clamped margins of the buttonhole-slit away from each other, so as to prevent stitching together the opposed edges of the buttonhole-slit. My present machine is a machine of said general type. This initial movement of the fabric is known as "spreading."

In the expired Reece patent, No. 240,546, the gooseneck of the machine carries the needles and a buttonhole-cutter, and this upper arm or gooseneck travels over the material held in a work-clamp attached to the bed of the machine, the said clamp traveling sufficiently to effect said initial or spreading movement of the marginal portions of the fabric around the buttonhole-slit. The feed-wheel or cam-disk j of this patent is rotated to effect the requisite movements of the machine by a friction-clutch j^2 , having a lever 5, which is in the path of a lever j^3 , vibrated by a suitable eccentric or cam w^3 , fast to a belt-wheel r , which wheel and cam are loose on the main shaft a^2 . The feed-wheel j is therefore given a step-by-step movement, and consequently there is some "lost time" in the operation of the machine, the mode of operation of which is, first, the work is inserted between the upper and under members of the work-clamp; second, the operator then moves the hand-lever p backward, and this movement of the hand-lever, which is at one side of the machine, causes the upper clamp members to pinch the work, the machine being then started and then com-

pling the entire cycle of operations—viz., third, movement of the cutting mechanism into cutting position in respect of the fabric between the clamp members; fourth, movement of the cutting mechanism to cut the buttonhole-slit; fifth, movement of the cutting mechanism away from cutting position, so as to permit the stitching operation to take place; sixth, the spreading of the fabric; seventh, the proper movement of the goose-neck over the clamped fabric and the operation of the stitching instrumentalities to stitch all but the small end of the buttonhole, (which is to be completed by "barring,") and, eighth, the automatic stopping of the machine and clamping of the work. Reece's United States Letters Patent No. 349,359, of September 21, 1886, recites that it is for an improvement on the machine of said Letters Patent No. 240,546. In this improved machine the feed-wheel *j* is also intermittently rotated by the intermittent throw of a friction clutch-dog; but mechanism is provided so that when desired by an increased throw of the clutch-dog the feed-wheel *j* may be rotated through a greater number of degrees of its circular path, so that the effective speed of the machine is greater than the effective speed of the machine of No. 240,546. In the machine of Patent No. 349,359 the throw of the hand-lever or handle 33 at one side of the machine simultaneously clamps the work and starts the machine.

Hill's United States Letters Patent No. 462,865, of November 10, 1891, recites that it is for an improvement on the machine of the Reece Patent No. 349,359. In this Hill patent machine the feed-wheel *j* is combined with a friction-clutch, whereby it is intermittently rotated, Hill's specific feed-wheel-actuating mechanism being constructed so as to have a longer throw than in the Reece Patent No. 349,359 in order to make the Hill type of Reece machine operate faster than the prior Reece machines of said two patents.

In Reece's United States Patent No. 494,280, of March 28, 1893, other improvements on the machine of the Reece Patent No. 349,359 are set forth, and both in the Hill patent as well as in said second Reece patent the operation which clamps the fabric also starts the machine simultaneously with the clamping movement. The same thing is true of the automatic buttonhole cutting and stitching machines shown in Reed and Dahl's United States Patent No. 450,844, of April 21, 1891.

An important feature of my improvement lies in dispensing with the old hand starting-levers of the prior art, which hand starting-levers were at a distance from the work-clamp, and in constructing the upper clamp member of my work-clamp in suchwise that it may be operated so as to clamp the work without thereby starting the machine, said upper clamp member being capable of receiving after the work is clamped a second and independent movement, whereby the machine is

started and the stitching mechanism set in motion and one or more complete stitches formed after the buttonhole has been cut and before the complete rotation of the cutter-operating and stitching-starting shaft has been effected. The advantages of this novel construction are that, first, the operator may unclamp the fabric and relocate it in the clamp if it has been improperly located therein, and, second, may thereafter start the machine by a further movement of the upper clamp member, whereon the operator's hand already is, without losing time by reaching out to another part of the machine in order to get hold of the starting device.

In said Reed and Dahl patents, as well as in my United States Patent No. 451,498, of May 5, 1891, the work-clamp is supported on a plate which moves in order to feed the margin of the buttonhole-slit around under the needles, which are supported in an upper arm or gooseneck which is stationary in respect of the bed-plate and turn-table. In the machines of these three patents the clamped fabric is between the times of operating the stitch-forming mechanism for the production of two buttonholes in succession automatically reciprocated between stitching and cutting positions. In my Patent No. 451,498 the moving work-plate was rotary, as in the old Union machine, while the moving work-plate of the Reed and Dahl patents was non-rotary.

In the Reed and Dahl patent, No. 450,950, the clamped fabric is jumped back and forth between these positions by means of the cam *c* and springs *c* co-operating with other parts. (Shown in Figs. 9 and 10 of that patent.) In my Patent No. 451,498 the same reciprocation is effected by means of the angle-lever *A*, one end of which is in engagement with the under cutter-lever of the machine and the other upper end of which engages the turn-table at the proper time to move it and the work-clamp carried by it from stitching position to cutting position and thence back again to initial stitching position after the buttonhole-slit has been cut preparatory to the stitching operation.

In the Hill and Reed and Dahl patents the time consumed in the cutting-feed period—that is, during the time in which the feed of the machine is operative to cut a buttonhole between the times of operating the stitch-forming instrumentalities for the production of two buttonholes in succession—is briefer or of shorter duration than the stitching-feed period. Such is also the case with the machine of my Patent No. 451,498. The rapid operation of the cutting mechanism between the stitching of two successive buttonholes has heretofore been considered as the proper way in which to proceed in order to produce an automatic buttonhole cutting and stitching machine of desired rapidity of operation; but I have discovered that still greater speed may be secured in machines of this class by making the cutting-feed period relatively

long and the stitching-feed period relatively short in comparison one with the other, and a novel and important feature of my improvement over the prior art lies in continuously feeding the clamped fabric throughout the entire stitching period.

In order to carry out mechanically and at a possible high rate of speed the method of my said Patent No. 461,841, of October 27, 1891, I have devised my present machine, which, mechanically considered, is a development of the machine shown in my said Patent No. 451,498, of May 5, 1891. In my present machine I use two upper needles and one under needle or "looper," while in my machine of Patent No. 451,498, as in the Reed and Dahl patent, No. 450,950, of April 21, 1891, only one upper needle was used. My new machine therefore is required to operate in a wholly new and peculiar manner in order to concatenate its three threads in carrying out the method of my said Patent No. 461,841.

The Reed and Dahl patent, No. 450,950, of April 21, 1891, granted on application filed April 21, 1890, and my Patent No. 451,498, of May 5, 1891, granted on application filed April 28, 1890, show two identical combinations, as follows: First, "The combination in a button-hole cutting and stitching machine, of automatic buttonhole-cutting mechanism actuated independently of the stitching mechanism, the buttonhole-stitching devices, and an actuating connection between the independent automatic buttonhole-cutting mechanism and the stitching mechanism whereby upon the completion of the operation of the buttonhole-cutting mechanism power is communicated automatically to the stitching mechanism and the stitching mechanism started," and, second, "In a buttonhole cutting and stitching machine, the combination with the stitching mechanism, of an automatic buttonhole-cutter, means independent of the stitch-forming mechanism for operating said cutter, a clamp-plate, work-clamps, and an automatic clamp-spreading device to operate to spread the clamps after the action of the cutter." The foregoing combination formed the issues of interference No. 15,069 in the United States Patent Office declared between the aforesaid applications, Serial No. 348,858, of Reed and Dahl, and Serial No. 349,809 of myself, March 4, 1891, and decided in my favor March 27, 1891, upon a written concession of priority signed by said Reed and Dahl and by the Globe Buttonhole Machine Company and filed in the Patent Office March 26, 1891.

One object of my present invention is to actuate the automatic buttonhole-cutting mechanism and stitching mechanism interdependently instead of independently, as in said two prior patents, and by so doing increase the efficient operating speed of the machine, as more fully pointed out hereinafter.

In the drawings illustrating the principle

of my invention and the best mode now known to me of applying that principle I illustrate my now preferred form of an automatic buttonhole cutting and stitching machine, whereof A is the upper arm or gooseneck, and A' the base-plate, which is conveniently mounted upon a bracket A² and pivotally connected therewith at a. Anvil or "brass" B is conveniently mounted in a vertically-reciprocating anvil-bar B', mounted in suitable ways in the front end of gooseneck A. The anvil-bar lever B² is pivoted at b in arm A and is loosely connected at b' with the anvil-bar. This anvil-bar lever B² is extended rearwardly of its pivot b and is connected with a link b², connected with an eccentric strap b³ on eccentric b⁴ of the transverse stitching-starting shaft B³. (See Figs. 1, 5, 11, and 12^A.) The stitching-starting shaft B³, mounted above and transversely of base-plate A', is provided with a triangular cam b⁵, which co-operates with the overhanging rear end of the under cutter-lever B⁴, (see Fig. 13,) which is pivoted at b⁶ in base-plate A'. The under cutter-lever B⁴ is provided at its front end with the reciprocating cutter B⁵, which co-operates with the anvil B. The front portion of the under cutter-lever B⁴ is provided with a link b⁷, (see Figs. 3 and 4,) which extends upwardly and is pivotally connected at b⁸ with the rocker-arm b⁹, pivoted in the depending lugs b¹⁰ on the under side of the base-plate A'. The free end of the rocker-arm b⁹ is provided with a cross-groove b^{10X} (see Fig. 41) and has a vertical hole which opens into the bottom of said groove and contains a latch-pin b¹¹, (see Fig. 41,) that is forced normally upward into said groove by spring b¹². This latch-pin has a lateral projection b¹³ through the side slot b¹⁴ in the rocker-arm, the purpose or function of this projection b¹³ being to force the latch-pin b¹¹ back against the tension of said spring b¹² when it comes into contact with the incline d²⁶ on the under side of the latch-releasing lever D. (See Figs. 24 and 25.)

In the present form of my machine the co-action of the projection b¹³ with the latch-releasing lever D when the cutting system of the machine is operated in connection with the fabric-clamping mechanism is as follows: When the cutter and cutter-anvil are in buttonhole-cutting position, the rocker-arm b⁹ is moved toward the front side of the machine, so that the projection b¹³ is out of contact with the latch-releasing lever D, and it is when the parts are in this position that the buttonhole is being cut. The fabric in which the buttonhole is to be cut is placed on the turn-table D', provided with the usual under jaws D² and upper jaws D³, (see Fig. 17,) capable of the usual clamping and spreading movements. The fabric is clamped between the under jaws D² and the upper jaws D³, which are carried by the rocking jaw-carrying frame d, hinged at d' to the latch-pin frame d², (see Figs. 17, 7, and 8,) and frame d is held up by the spring d³. The frame d

- is formed with two jaw-supporting arms d^4 and is moved downwardly against the tension of spring d^3 by the clamping-lever D^4 , pivoted in the uprights d^{2x} of latch-pin frame d^2 5 and provided with an ear d^5 , which impinges on spring d^3 . The pivoted end of lever D^4 is provided with a pair of cam-lugs d^6 , (see Fig. 1,) which when lever D^4 is moved down press on the arms d^4 of the upper-jaw-carrying frame d and moves said upper jaws tightly upon the fabric to be clamped, but without thereby starting the machine, another further and independent movement of the clamping-lever D^4 being required to start the machine. 10 15 The outer end of the latch-pin frame d^2 (of which the uprights d^{2x} are preferably an integral part) is provided with an open slot d^7 , which spans the upper end of the latch-pin b^{11} . The construction and said arrangement 20 of the latch-pin frame and latch-pin b^{11} will be best understood from Figs. 7 and 41. It is by these means in the present form of my machine that the turn-table D' is mechanically connected with the rocker-arm b^9 , so as 25 to be reciprocated from stitching position, whereat the fabric is clamped, to cutting position and back into stitching position. The function of the latch-pin is to prevent the turn-table and thereby supported work-clamp 30 from turning or tending to turn during the time that the turn-table and supported work-clamp are being reciprocated between the cutting and stitching positions. The clamping mechanism thus described is provided with 35 the usual spreader D^5 , provided with a spreading-cam d^8 , which is in the form of an eccentric-tube mounted on post d^{8x} , fast on turn-table D' . Cam d^8 engages the inner sides of the arms d^4 , which support the upper jaws 40 D^8 and also engage the inner sides of the rear parts of the under jaws D^2 , and, as heretofore, when the upper and under jaws are firmly pressed together on interposed fabric the opposite sets of jaws may be "spread" 45 or moved apart after the hole is cut by swinging the spreader-lever D^5 . By this lateral movement of the pairs of clamping-jaws away from each other the spreading of the fabric is effected. Spreader-lever D^5 is moved automatically, as hereinafter described. 50 The latch-pin frame d^2 is provided with a feeding-pin P , which passes down through the turn-table and thence through the opening a^6 in the cover-plate a^5 into the space f^5 , 55 which opens into the feeding-pin groove f^6 of the feed-wheel F . (See Figs. 7, 18, and 5.) The rear end of the latching-pin frame d^2 is provided on its upper side with an incline d^{2xx} , and the upper end of the rocker-arm b^9 60 is provided with a cap d^{10} , the incline d^{11} of which overlaps the incline d^{2xx} on the outer end of the latch-pin frame d^2 (see Figs. 6 and 8) and so prevents the latch-pin frame from becoming accidentally lifted or sprung off 65 from the latch-pin b^{11} . The upper surface of the cap d^{10} has the cam-surfaces d^{12} , (see Fig. 8,) against which the outer end portion of the

spreader-lever D^5 operates automatically for the automatic spreading of the upper and lower clamping-jaws after the turn-table begins its stitching-feed movement, the feed-wheel F , through its feeding-pin connection with the turn-table and thereby-supported parts, compelling rotation of the turn-table, and thereby moving spreading-lever D^5 into engagement with the cam-surface d^{12} shortly after a part of the buttonhole-slit has been stitched. 70 75

The stitching-starting shaft B^3 is provided with a worm-gear b^{16} , which meshes with a worm b^{17} on the drive-shaft B^{5x} , which is also provided with a fast pulley b^{18} . In accordance with my present invention the stitching and cutting mechanisms are interdependent, the stitching-starting shaft B^3 being provided 85 with means for setting the cutter system in operation and the latter being inoperative unless having a mechanical connection with the stitching-starting mechanism. 90

Revolution of stitching-starting shaft B^3 causes the high point of the eccentric b^4 (fixed on the shaft) to move, so as to pull the link b^2 downwardly, and thereby pull downwardly the rear end of the upper cutter-lever B^2 , so as to move the anvil-bar B' and anvil B out 95 of contact with the fabric and out of the path of the clamping mechanism. The same revolution of the stitching-starting shaft B^3 causes the high point of the triangular cam b^5 (fixed on the shaft) to engage the hook b^{19} , which 100 forms the rear end of the under cutter-lever B^4 , so that the front end of the under cutter-lever B^4 is lowered, and the cutter B^5 is thereby carried out of the buttonhole-slit in the fabric and down through the opening d^{13} of 105 the turn-table D' . Center plate f' is fast on the hub a' , projecting upwardly from the base-plate A' of the machine. (See Figs. 5, 12^A, and 18.) This hub a' forms the bearing 110 for the feed-wheel F . The center plate f' is provided with an upwardly-projecting button or throat-plate f^2 , which projects up into the longitudinal slot d^{13} of the turn-table D' and forms a stationary guide-bearing therefor during the reciprocating and turning 115 movements of the turn-table and clamping mechanism supported thereon. (See Fig. 12^A.) The button or throat-plate f^2 is provided with the needle-passage f^3 , one portion 120 of which receives one upper needle and another portion of which receives the other upper needle. Continued rotation of the stitching-starting shaft B^3 rotates the driving-pin carrier d^{14} , (see Fig. 11,) which is fast on said shaft and is provided with the endwise-movable 125 driving-pin d^{15} , that is projected into one or another of the driving-pin holes d^{16} on the inner side face of the worm-gear b^{16} , so as to couple the driving-pin carrier and worm-gear b^{16} together and to compel them to rotate co- 130 incidentally. This provision of the stitching-starting shaft B^3 with a power-driven member and with a movable clutch member follows the construction of the expired Reece

patent, No. 240,546, wherein the stitching-starting shaft a^2 is provided with a pulley r and clutch member r^4 , and wherein the stitching-shaft a^2 , like my stitching-starting shaft, 5 is mounted transversely of the machine and sets the stitching mechanism in operation. In detail my construction differs from the old Reece construction. The worm-gear b^{16} and the driving-pin carrier d^{14} are coupled together during the cutting operation and during the return of the cutter and anvil to their positions of rest; but to prevent the continuous operation of the cutter and cutter-anvil—that is, to prevent their operating while the 15 buttonhole is being stitched—it is necessary to uncouple the worm-gear b^{16} from the driving-pin carrier d^{14} , so that the worm-gear may run free and the cutting mechanism remain inoperative—that is, as in the expired Reece 20 patent, No. 240,546, the stitching operation does not begin until after the cutting operation is finished. When the driving-pin d^{15} , which is held forward in a hole d^{16} under the stress of the driving-pin spring d^{17} , (see Figs. 25 3, 5, and 11,) is brought around by the rotation of the stitching-starting shaft B^3 toward the outer wedge-shaped end d^{18} of the cutter-starting lever d^{19} , the cam-faced lug d^{20} of the driving-pin rides the incline d^{21} on said outer 30 end d^{18} of the cutter-starting lever d^{19} , and the driving-pin d^{15} is thereby withdrawn from its hole d^{16} and out of engagement with the worm-gear b^{16} . The spring d^{17} , the free end of which engages the head of the driving-pin 35 a^{15} , is also useful to keep the driving-pin from rattling and wearing when it is drawn back by the wedge-shaped end d^{18} of the cutter-starting lever d^{19} . The cutter-starting lever d^{19} is pivoted at d^{22} to the base-plate of the 40 machine, and its forward end d^{24} is held down by the spring d^{23} , (see Fig. 3,) and the rear portion of the cutter-starting lever d^{19} , where it is provided with the incline d^{21} , is thereby held in contact with the cam-head of the 45 driving-pin d^{15} . The forward end d^{24} of the cutter-starting lever d^{19} extends upwardly through a hole a^2 in the base-plate of the machine, (see Figs. 3, 4, and 7,) and during the time that the cutting mechanism remains inoperative—that is to say, during the time 50 that the stitch-feeding and stitching operations are going on—this end d^{24} of lever d^{19} is either just out of contact with or in sliding contact with the under surface of the feed-wheel F , which is provided on its under side with a hole d^{25} , (see Figs. 3 and 5,) into which the upper front end d^{24} of the cutter-starting lever d^{19} may enter in order that the rear end of the cutter-starting lever d^{19} may be 55 moved downwardly out of the path of the driving-pin d^{15} and permit the driving-pin to enter one of the holes d^{16} in the worm-gear under the tension of its spring d^{17} .

Except when the upper end d^{24} of the cutter-starter lever d^{19} is opposite the hole d^{25} on the under side of the feed-wheel F it is impossible to move the cutter-starter lever d^{19} , and

consequently it is impossible to set the cutting mechanism in operation. This is a very important feature of my invention, because 70 it makes it impossible for the operator of my new machine to accidentally start the cutting mechanism into operation while the stitching operation is taking place. A good deal of difficulty has been hitherto encountered in 75 the operation of this type of machine by the accidental starting of the cutting mechanism at a time when the turn-table was moved out of its proper position for the cutting operation, and it is therefore very important in 80 order to prevent the anvil or cutter from bringing up against a solid portion of the turn-table or clamps to obtain a construction that renders a starting of the cutting mechanism impossible except when the turn-table 85 is in proper position for cutting.

The inward movement of the rocker-arm b^9 , connected, as above stated, with the turn-table, moves the turn-table and the work-clamp thereon into position for stitching, this movement being in the direction of the length of the buttonhole-slit. When the turn-table and clamps have thus been moved so as to bring the buttonhole-slit into stitching position, the turn-table and clamping mechanism 90 are to be moved in proper relation to the stitching instrumentalities by rotation of the feed-wheel F . It is therefore necessary that the turn-table and clamping mechanism be disconnected—that is, that the clamping-pin frame d^2 should be released from engagement with the latch-pin b^{11} . The latch-pin b^{11} is therefore withdrawn out of the open slot d^7 in the clamping-pin frame d^2 , and to this end the slot b^{10X} (see Fig. 6) in the upper end of the rocker-arm b^9 is made open-ended, so that the downwardly-projecting lug d^{2XXX} of the clamping-pin frame, in which lug the said open slot d^7 is received, may be moved out of engagement with the rocker-arm b^9 . As the 100 upper end of the rocker-arm b^9 pushes the work-plate and the clamping mechanism forwardly from cutting into stitching position the projection b^{13} moves under the downward incline d^{26} of the clamp-releasing lever D , 105 which is pivoted at d^{27} to the bed of the machine and held normally against the side of the rocker-arm b^9 by the spring d^{28} . Said projection b^{13} is moved downwardly by its engagement with the incline d^{26} , withdrawing the 110 latch-pin from engagement with the slot d^7 . (See Fig. 41.) The free end d^{29} of the clamp-pin-releasing lever D projects into the path of a lug f^{4X} of the feed-wheel F . (See Fig. 5.) When the turn-table and clamping mechanism 115 carried thereby are moved into position for the stitching of the buttonhole-slit, the lower end of the feed-pin P is carried through the open portion f^5 of the feeding-pin groove f^6 into the path of the feed-wheel follower F' . This follower is hinged at f^7 to the feed-wheel 120 and travels with the feed-wheel, and while its tooth f^8 is in contact with the feed-pin P , which passes through the turn-table D' and

the feed-pin groove f^9 , the turn-table and the clamping mechanism carried thereby are compelled to move with the feed-wheel. The inner surface of the follower F' presses upon 5 the opposed cam-surface a^{2x} (see Fig. 5) of the hub a' , and from the starting-point until the feed-wheel has made a quarter of a revolution the follower F' is held in one and the same position with relation to the feed-pin 10 P , both traveling together. When follower F' has traveled a quarter of a revolution, then its rear surface is brought opposite a recess a^3 in the cam-surface a^{2x} of the hub a' and the follower F' falls back into the recess a^3 15 and out of contact with the feed-pin P , being dragged past and out of contact with the feeding-pin by the continued rotation of the feed-wheel F , which rotates continuously. This quarter-revolution carries the work- 20 plate and clamping mechanism carried thereby (and holding the fabric) from the middle of the small end wall of the buttonhole up to the beginning of the first straight side—that is, from z to z' in the buttonhole shown in 25 Fig. 29. The moment that the follower F' passes out of contact with the feed-pin P the lower end of the feed-pin is engaged by the walls at f^{8x} of the groove f^6 . When the feed-pin P is at the starting-point, it passes through 30 the guideway f^9 , formed between the opposed edges of the center plate f' and of the cover-plate a^5 , having an irregular opening, within 35 which the center plate f' is mounted. (See Figs. 18 and 12^A.) The opening in the cover-plate a^5 is provided with a slot a^6 , through 40 which the feed-pin P is moved in a right line in the direction of the length of the button-hole-slit as the work-plate D' is moved from the front toward the rear of the machine and 45 back again. This to-and-fro movement of the turn-table takes place during the cutting operation. When feed-pin P is moved out of the slot a^6 into guideway f^9 , it is brought into the position shown in Fig. 5, and 50 (the buttonhole having been cut) the feed-pin is in position to travel through guideway f^9 , as it is pushed by the contact therewith of the follower F' and delivered to the walls of the cam-groove f^6 . When the walls of the feed- 55 cam groove f^6 begin to push upon the feeding-pin P at the time that the follower F' drops into the recess a^3 , the feeding-pin will be carried through the straight space at X' , the follower F' having first drawn the feed-pin 60 through the curved space X^4 of the guideway f^9 . The formation of the first straight side of the buttonhole begins to take place as the feed-pin P is moved through the straight space at X' . During the time that the feed- 65 pin is being pushed from its starting position (shown in Figs. 5 and 18) to the straight space at X' one-half of the small end of the buttonhole is being stitched. The feed-pin P being thus carried toward the center of the machine and being guided by the opposed edges of the guideway f^9 and finally drawn out of the straight space at X' , the second

follower F^2 engages the feed-pin and moves the feed-pin through the curved portion X^2 of the guideway f^9 until the feed-pin is 70 brought to the straight portion at X^3 of guideway f^9 , this straight portion at X^3 being opposite the straight portion at X' . During the time that the feed-pin is traveling from the straight portion at X' to the straight portion at X^3 the large or eye end of the buttonhole is being stitched. The eye of the buttonhole is stitched while the feed-pin passes through this curved portion X^2 . The second or last straight side of the buttonhole 80 is stitched when the feed-pin travels through the second straight portion at X^3 . The second follower F^2 is loosely pivoted to the feed-wheel and is carried thereby opposite the recess f^{10} in the hub a' , dragging past the lower 85 end of the feed-pin and permitting the feed-pin to travel through the straight part at X^3 of the guideway by its engagement with walls of the cam-groove f^6 . Thereupon the follower F' having been brought around by the 90 feed-wheel engages the feed-pin and carries it through the curved portion X^4 of the guideway f^9 to the point of beginning, then completing the remaining half of the small end of the buttonhole. When the follower F' engages 95 the feed-pin P the second time, its shoulder f^{11} is the part that impinges on the feed-pin and carries it to the point of beginning, where the rear shoulder f^{12} of the follower F' recedes into recess f^{13} in hub a' . The feed-pin 100 and clamping mechanism carried thereby are thus given one complete movement for carrying the buttonhole-slit entirely around for the stitching of the buttonhole. The feed-wheel F , however, makes two full revolutions 105 for the making of a single buttonhole.

Feed-wheel F is formed with a peripheral gear f^{14} , which meshes with a gear f^{15} , the shaft f^{16} of which is journaled in a suitable bearing in the base-plate of the machine. 110 Shaft f^{16} is provided below the under side of the base-plate with a gear f^{17} . This gear f^{17} meshes with the worm G , carried by the under driving-shaft G' , which at its outer end is provided with the driving-pulley G^2 . When the 115 buttonhole has been stitched, the machine is automatically stopped to give the operator the opportunity for resetting the fabric in the clamping mechanism for a new buttonhole. The automatic stopping of the machine at the 120 completion of the buttonhole is effected in the present instance by the following instrumentalities: Said shaft f^{16} is provided with a fixed gear f^{18} , which meshes with a gear f^{19} , fast on the hub f^{20} , which is journaled in the 125 bed-plate of the machine. A stop-lever F^3 (for stopping the machine at the completion of each buttonhole) is fulcrumed on said hub f^{20} eccentrically of the center thereof. (See Fig. 3.) This stop-lever F^3 is formed toward 130 its front end with a laterally-projecting arm f^{21} , which is at an angle to its front hook-shaped end f^{22} . (See Figs. 3 and 20.) Its rear end extends rearwardly of the machine and

is adapted to coöperate at the proper time with the arm f^{23} of the three-armed rocker R, the hub of which is loosely mounted on a disk fixed on the stitching-starting shaft B³. (See Figs. 5, 11, and 21.) Said hook end f^{22} engages a lug or shoulder f^{24} on the transverse rocker-bar F⁴, fulcrumed in suitable bearings f^{25} on the under side of the base-plate. (See Figs. 3 and 23.) During the time that the stitching mechanism is stitching the stop-lever F³ is out of interlocking engagement with the transverse rocker-bar F⁴, this disengagement being effected by contact of the incline f^{26} on the uppersurface of the under cutter-lever B⁴ (see Fig. 13) with the laterally-projecting arm f^{21} , Figs. 3, 4, 13, and 20, of the stop-lever F³, said incline f^{26} when the cutter-carrying end of the under cutter-lever is down rocking the stop-lever F³ on its fulcrum, thereby moving the hook end f^{22} out of the path of the rocker-lever F⁴. A spring f^{21X} holds arm f^{21} in contact with the incline f^{26} (see Fig. 13) at one time during the operation of the machine and holds the stop-lever F³ in proper working position. When the front or cutter-carrying end of the under cutter-lever B⁴ is moved upwardly to cut a buttonhole, said incline f^{26} will engage said laterally-projecting arm f^{21} of the stop-lever F³, and thereby move the hooked end f^{22} of the stop-lever F³ out of contact with said rocker-bar F⁴. (See Figs. 3 and 13.) The rocker-bar F⁴ is provided with a contact-surface f^{27} , against which a shoulder f^{28} on the upper edge of the under cutter-lever B⁴ contacts immediately after said disengagement of stop-lever F³ with the transverse rocker-bar F⁴. (See Fig. 13.) Said shoulder f^{28} bears against said contact-surface f^{27} and holds the transverse rocker-shaft F⁴ back positively for the purpose now to be explained. The transverse rocker-bar F⁴ is provided with a bearing-lug f^{28X} , (see Figs. 3, 4, and 23,) which at a certain time comes into engagement with a lug f^{29} on the worm feed-gear F¹⁷, thereby locking the gear and preventing the further rotation of said gear, and consequently further movement of the feeding and stitching mechanisms, or, in other words, of the machine; but during the time that the transverse rocker-bar F⁴ is held back by means of the upward movement of the forward end of the under cutter-lever B⁴ said shoulder f^{28} of the transverse rocker-bar is kept out of the path of said lug f^{29} on the back of gear F¹⁷, so that the machine is free to feed and stitch. A suitably-mounted spring f^{30} , Fig. 13, keeps the rocker-bar F⁴ in its upper position after the cutter-lever B⁴ returns to position of rest.

As above stated, the feed-wheel F makes two revolutions for each buttonhole, and the gear F¹⁵, that meshes with the feed-wheel F, also makes two revolutions for each buttonhole. Gear F¹⁸, however, is only one-half the effective diameter of the gear F¹⁹. The consequence is that the hub F²⁰, upon which the gear F¹⁹ is fast, makes but one revolution to

every two revolutions of the gear F¹⁵, or, in other words, but one revolution during the feeding and stitching of the buttonhole. 70

At the completion of the buttonhole the stop-lever F³, eccentrically mounted on and carried by the hub F²⁰, is so moved that its hooked end f^{22} engages the shoulder f^{24} on the transverse rocker-bar F⁴ and rocks the 75 transverse rocker-bar, so as to bring the end of its bearing-lug f^{28X} into the path of the lug F²⁹ on the feed worm-gear F¹⁷. Consequently the machine is stopped; but just prior to said contact the rear end of the stop-lever F³ is carried against the downwardly-projecting arm f^{23} of the three-armed rocker R on the transverse stitching-starting shaft B³. When arm f^{23} is thus engaged, the other arm f^{30} is rocked into engagement with the 80 shaft-connector F³¹, which is loosely mounted on an eccentric F^{31X}, fast on said shaft B³, the tooth F³² of which is during the stitching operation in contact with the shoulder F³³ (see Figs. 2 and 10) of the belt-shipper F³⁴, 85 the fork F³⁵ whereof engages the edges of the driving-belt and holds the belt upon said driving-pulley G²; but when said arm F³⁰ is rocked upwardly said shaft-connector F³¹ is lifted out of engagement with the belt-shipper 90 F³⁴, which is then rocked by the action of the spring F³⁶, (see Figs. 1 and 3,) so as to pull the belt from the fast pulley G² onto the loose pulley G³. The belt-shipper F³⁴ has a 95 downwardly-projecting lug F⁴², which engages on the inner face of the bracket A², in which the loose pulley G³ is journaled, when the belt-shipper is in the position to hold the belt on the loose pulley. The belt-shipper F³⁴ is pivoted at F³⁷ on the supported bracket A² of 100 the machine. The belt-shipper is conveniently provided with a handle F³⁸.

If it is desired to stop the machine, for example, when a thread breaks or in adjusting the machine, the thumb-lever F³⁹, fulcrumed 110 to the frame at F⁴⁰, Fig. 5, with its inner end under the shaft-connector F³¹, may be depressed. A spring F⁴¹ (see Fig. 12A) throughout the stitching operation holds the shoulder F³² of the shaft-connector F³¹, loosely mounted 115 on the eccentric, fast on the stitching-starting shaft B³ against the projection F³³ of the belt-shipper. Consequently the stitching-starting shaft B³, which is used to actuate the cutting mechanism, also performs the function of, 120 first, making a mechanical connection by moving the shaft-connector F³¹ with the stitching mechanism, and, secondly, maintaining that mechanical connection of the stitching-starting shaft B³ with the stitching mechanism 125 throughout the entire stitch-feeding and stitching operations of the machine. When the eccentric on which the shaft-connector F³¹ is mounted thrusts said pawl toward the rear of the machine, it thereby moves the 130 belt-shipper fork F³⁵ so as to throw the belt on the loose pulley G³ on the bracket A² of the machine upon the pulley G², which is fast on the undershaft G'. This interdependence

of the stitching-starting shaft, which also by the described mechanical connections operates the cutting mechanism with the button-hole-stitching mechanism of the machine, is a novel feature of my present invention, and the high efficiency of my present machine is in part due to the fact that the eccentric f^{31X} , on which the shaft-connector f^{31} is mounted, is so shaped and timed that the stitching operation is begun before the upper and under cutter-levers have moved back to normal position. This also is a feature of novelty, for heretofore the stitching mechanism has not been set in motion until after the cutting mechanism has come to a rest. Consequently by my present invention I effect a certain saving of time in the operation of the machine, which saving, taken in connection with savings of time at other points of the machine, results in a machine of much higher speed than any heretofore produced, so far as I am advised. In this connection I now point out that the under cutter-lever in consequence of the shape of the triangular eccentric b^5 is moved away from its cutting position at a much higher rate of speed than the upper cutter is moved away from its cutting position. This high speed of the return movement of the under cutter-lever B^4 gives a high-speed pull to the link b^7 , whereby the rocker-arm b^9 , which is in engagement with the turn-table, is given a high speed during the time that it pushes the turn-table from cutting position into initial stitching position, and immediately upon the movement of the turn-table into initial stitching position the stitching mechanism is started up by the practically instantaneous outward end thrust of the shaft-connector f^{31} ; but an important point to be observed by persons making machines to embody my present invention is to so time the triangular eccentric b^5 and the eccentric of the shaft-connector f^{31} that the high point of the latter eccentric shall effect the outward end thrust of said shaft-connector f^{31} almost simultaneously with the engagement of the high point of the triangular cam with the overhanging arm b^{19} of the under cutter-lever. In my Patent No. 451,498, of May 5, 1891, by means of the angle-lever A^{26} of the under cutter-lever A^7 , I secured a quick return of the turn-table from cutting to initial stitching position; but I did not in said patent make the spindle-shaft a^6 , which drove the cutter system, interdependent with the stitching mechanism, as in my present machine, because in the machine of said Patent No. 451,498 I threw the worm A^{11} out of connection with the worm-gear A^4 on said spindle-shaft A^5 as soon as the buttonhole was cut, so that there was no mechanical connection between the spindle-shaft and the stitching-shaft B of the machine during the time that the stitching operation was going on. It will be observed that by my present construction I dispense with clutch members on the stitching-shaft and that the only clutch members required in my machine are those upon the stitching-starting shaft—to wit, the worm-gear b^{16} on the driving-pin carrier d^{14} 70 and its parts. It is to be noted also that the stitching-starting shaft B^3 during the latter part of its rotation for the operation of the cutting system starts the stitching instrumentalities into operation and that the shaft B^3 75 is not automatically stopped until after the stitching of one side of one portion of the small end of the buttonhole is begun. This is due to the timing of the triangular eccentric b^5 and of the eccentric on which the shaft-connector f^{31} is mounted, and hence it is that rotation of the stitching-starting shaft B^3 is required to effect the stitching of one portion of the small end of the buttonhole. The stitching-starting shaft consequently is also 80 a stitching-shaft in my machine. It starts the stitching, or effects by its rotation the stitching of a portion of the small end of the buttonhole, and by holding its eccentric f^{31X} with the high point thereof toward the rear 85 end of the machine holds the shaft-connector f^{31} in its outer position and, in conjunction with the spring f^4 , (the spring being to prevent accidental displacement of the shaft-connector with the belt-shipper,) maintains 90 the stitching-feed movement of the machine and the stitching operation of the machine throughout the stitching of the buttonhole. During a part of the rotation of said shaft B^3 it is not only actuating the cutting mechanism, but it is simultaneously operative in effecting the initial stitching of the buttonhole. By driving the stitching-starting shaft B^3 by the worm-gear b^{16} and rotating worm b^{17} I avoid the actuation of the shaft B^3 by a belt. 95 If the shaft B^3 were actuated by a belt to a pulley thereon, then during the cutting operation, when there is a good deal of resistance offered by the material to be cut to the strain of the belt, the belt will tend to slip, 100 and the practical result will be that the cutter will not be properly operative and will remain stationary in the work and against the cutter-brass. By the use of the worm-gear and worm the strain that is brought upon the 105 actuating devices of the cutting mechanism during the cutting operation is distributed, and the practical result is that by the employment of the worm-gear and worm for driving the shaft B^3 the cutting mechanism is operated with much more power and at a greater 110 speed than would be possible by the use of a pulley, and this increased rapidity of operation of the cutting system also brings the stitching system into operation sooner than 115 heretofore, and thus the high effective speed of my machine is in part due to the employment of the worm and worm-gear for driving the stitching-starting shaft, whereby the interdependent cutting and stitching mechanisms are properly operated with increased 120 relative speed and reliability and the parts come into operation at the proper time one 125 in relation to the other. The slip of the belt 130

during the cutting operation would affect the relative movements of the timed parts. In a word, the operation of the interdependent cutting and stitching mechanisms is positive, and it is in consequence of these positive operations of said mechanisms that I do not require to stop the shaft B^3 until after a part of the buttonhole-stitching has been effected.

10 In the gooseneck there is mounted the usual needle-bar shaft H , provided with the needle-bar-driving flange h , from which the link h' extends to the needle-bar clasp h^2 , the needle-bar h^3 being mounted vertically, as usual, in the gooseneck and is provided with two thread-carrying needles $h^4 h^5$, which pass through the needle-passage f^3 of the throat-plate f^2 during the formation of the buttonhole. One needle h^4 passes within the buttonhole-slit 15 and the other needle h^5 passes through the fabric outside of the buttonhole-slit. The gooseneck also carries the interlacer I , the office of which is to lay a thread in a bight from the fabric-penetrating needle h^5 to the buttonhole-slit-penetrating needle h^4 . This interlacer I is mounted in a lengthwise-reciprocating carrier i , which is mounted in a bracket i^2 , journaled on the horizontal pivot i^3 . The interlacer-carrier i is connected with 20 an eccentric-strap i^4 , within which is the eccentric i^5 , the latter being fast on the shaft H . Rotation of the needle-bar shaft H therefore both reciprocates the needles and gives the interlacer its bight-forming movement, which 25 is a complex one, due both to the movement of its bracket on the horizontal pivot and to the other movements which are derived from said eccentric.

The rear portion of the needle-bar shaft H 30 is provided with two cranks $i^6 i^7$, these being quarter-turn cranks. A suitable connecting-rod i^8 connects crank i^6 with the crank i^9 on the understitching-shaft G' . Another link i^{10} connects the crank i^7 with a crank i^{11} on 35 said lower shaft G' . Shaft H is conveniently provided with a hand-wheel i^{12} , so that the machine may be operated by hand for adjustment and the like; but this hand-wheel i^{12} is not a necessary part of the machine.

40 The thread-releasing lever K is pivoted on the gooseneck, Fig. 1, its rear end being provided with a downwardly-extending hook k , Fig. 1, which overlaps the vertical arm k' of the three-armed rocker R . Said vertical arm k' is provided on its rear face, preferably, with a spring k^2 , the upper end of which projects outwardly, so as to contact with the hook k , and the position of the upper end of the spring is adjusted by the screw k^3 . The purpose 45 of this regulation is to compel the thread-releasing lever K to operate the thread-tension devices at the proper time. Said arm k' is rocked toward the front end of the machine by the stop-lever F^3 engaging the arm f^{23} of the rocker R in consequence of the rotation 50 of the hub f^{20} . The rear end of the thread-

70 releasing lever K is moved upwardly on its pivot k^4 , Fig. 1, by the overlapping of its hooked arm k upon the rear end of the upper cutter-lever B^2 . The front end of the thread-releasing lever K is U-shaped, and when it is moved downwardly it carries its arms $t t'$ of the U from between the thread-tension disks $t^2 t^3$, loosely mounted on the stud t^4 through bracket t^5 . Each pair of tension-disks is provided with a spring t^6 . The tension-opening end of the thread-releasing lever K is moved downwardly against the force of a spring k^6 , conveniently interposed between the gooseneck and under side of lever K . As the 80 threads are required to be under tension during the feeding and stitching operations, the tension-spreading end of the thread-releasing lever K is held out of contact with the tension-disks during the feeding and stitching 85 operations, and this is accomplished by the upward movement of the rear portion of the upper cutter-lever B^2 , the upper surface of which rises into engagement with the overlapping hook end k^7 of the upwardly-extending arm k^8 of the thread-releasing lever K , whereby the hooked end k of the lever K is lifted above the upper end of spring k^2 , which then moves (in consequence of the tension of spring f^{41}) rearwardly under hook end k . 90 The end of hook end k then rests on the top end of spring k^2 and remains there during the feeding and stitching operations, so that the upper threads are under tension during 95 said operations. The thread-releasing lever 100 K is moved out of engagement with the tension-disks at the time the rear end of the upper cutter-lever B^2 reaches its highest position, at which time the anvil or brass B is at its lowest position and the buttonhole has 105 just been cut. When the last buttonhole-stitch is made, the stop-lever F^3 engages the arm f^{23} of the three-armed rocker R and moves the spring k^2 out from under the hook end k of the thread-releasing lever K , 110 the front of which in consequence of the expansion of spring k^6 is thereupon forced between the tension-disks, so that the two upper threads are relieved from tension at the completion of the buttonhole, whereby the 115 operator is enabled to more readily move the work preparatory to the clamping thereof for the next buttonhole-cutting operation.

The understitching-shaft G' is provided at 120 its front end (see Figs. 3, 4, 7, and 12^A) with a spreading-cam L , into the groove l of which the cam-roll l' on the lever l^2 , pivoted at l^3 on the under side of the base-plate, projects. Lever l^2 is provided with an upwardly-projecting arm l^4 , (see Figs. 4 and 7,) which supports the spreader L' for the under thread. On the cam L a link l^5 is eccentrically mounted at z , (see Figs. 4 and 6,) this link being loosely pinned at l^6 to the looper-rocker arm l^7 on the horizontal pivot l^8 in the base-plate 130 of the machine. The cam L is made fast on the shaft G' , conveniently by a set-screw z' ,

as shown in Fig. 3. The looper (or under-thread-carrying needle) is marked L^2 . Rotation of the under driving-shaft G'' causes the under-thread-carrying needle L^2 to pass the under thread through the thread-loops formed by the upper needles and to leave its under thread on the spreader L' , which is moved in the arc of a circle, its path being in a horizontal plane, to penetrate the loop of the under thread. The loop of the under thread is held spread open by the spreader L' until the next descent of the upper needles.

An under-thread cutter M , Fig. 42, severs the thread at the completion of the button-hole and is mounted on the vertical pivot m and held normally in position for cutting by the engagement of its tailpiece m' with the tripping-lever m^2 , which is pivoted at m^3 on the bed. (See Figs. 4 and 5.) The upper end 20 of the tripping-lever m^2 (see Fig. 10) projects up through the bed of the machine and is provided with a lip which is adapted to engage with the pawl m^4 , loosely pinned on the cloth-clamping lever D^4 , so that the operator on 25 lifting up the cloth-clamping lever to release the fabric thereby moves the lip m^5 (see Figs. 1, 10, and 17) of pawl m^4 against the lip on the outer end of the tripping-lever m^2 , which is thereby carried out of interlocking engagement 30 with the tail m' of the cutter M . A suitable spring m^8 , Figs. 7 and 42, is mounted on the pivot of the cutter M , with one end in engagement with the cutter and the other end engaged with the bed-plate, so that when the 35 tail m' of the cutter M is released from engagement with the tripping-lever m^2 the spring will move the cutter to sever the under thread automatically, because the tripping-lever m^2 while in engagement with the tail m' holds 40 the cutter M away from its thread-cutting position against the tension of spring m^8 . After the cutter M severs the thread at the completion of a buttonhole the rise of the forward part of the under cutter-lever B^4 for cutting 45 a new buttonhole brings the wall m^6 of the upper surface of the cutter-lever B^4 (see Fig. 13) against the thread-cutter M on the cutter side of its pivot, and thus forces the tail m' of cutter M past the inner end of the tripping-lever m^2 , (see Fig. 13,) which thereupon by 50 reason of the tension of the spring m^8 (see Figs. 7 and 42) flies into position back of the rear edge of the tailpiece m' , (see Fig. 3,) and so interlocking therewith holds the cutter M out of cutting position. One end of spring m^8 is fast in the cutter and the other in the frame, the spring being coiled around the pivot m of the cutter. The spring and cutter are shown detached in Fig. 42. When 55 the upwardly-moving under cutter-lever presses against the cutter M to carry its tail m' past the inner end of the tripping-lever, it then causes spring m^8 to be compressed. When the tripping-lever m^2 is depressed, it 60 is carried out of interlocking engagement with tail m' , and consequently the spring m^8 will automatically move the cutter to sever the

under thread at the completion of the buttonhole.

In order to keep the machine constantly supplied with the under thread, it is necessary at the completion of the buttonhole to pull off a certain amount of thread to supply the under needle or looper L^2 when the thread is cut, and this is accomplished by the under-thread pull-off N , (see Fig. 3,) carried by the transverse rocker-shaft F^4 , (see Figs. 3 and 23,) and therefore having a swinging movement at the free end which is formed with the thread-eye n . (See Fig. 4.) The under tension device N' is shown in Fig. 4 and is of familiar construction.

In order to dispense with the thread-take-up levers, I provide my present machine with an angular bracket Q , (see Fig. 4,) which is mounted on the frame and is provided with thread-guide holes q . The upwardly-extending arm of the bracket has a slot q' at its upper end, and the upper end of said arm is drilled to receive the spiral springs q^2 in a vertical position. (See Fig. 9.) Thread-tension arms are pivoted in slot q' at q^3 and have heads q^4 , against the under surface of which the springs q^2 press to force the downwardly-projecting portions of the thread-tension arms Q' toward the side edges of the bracket Q . The upper threads are carried each between a thread-tension arm and an opposed edge of the bracket, and the springs q^2 exert sufficient pressure to cause friction upon the threads which pass from the tension-arms q' through the guide-holes q to the upper needles. Rearwardly of the upper arm of bracket Q the needle-bar h^3 rises, and the upper end portion of the needle-bar is provided with laterally-projecting arms $q^5 q^6$, the arm q^5 controlling the thread which is furnished to the fabric-penetrating needle h^5 and the arm q^6 controlling the thread which is furnished to the buttonhole-slit-penetrating needle h^4 . The arm q^5 is farther away from the eye of the fabric-penetrating needle h^5 than the arm q^6 is away from the eye of the buttonhole-slit-penetrating needle, the difference between these distances being approximately three-eighths of an inch. After the concatenation of the threads of each stitch the upwardly-moving arms $q^5 q^6$ strike the upper threads and set the stitch, and as more thread is required by the fabric-penetrating needle in the formation of each stitch than is required by the buttonhole-slit-penetrating needle the arm q^5 , which controls the thread for the fabric-penetrating needle, strikes its thread first, so as to pull a little more thread from the spool than the arm q^6 draws from its spool at the time the stitch is set. Thus the upwardly-moving arms both set the stitch and draw off thread from the spools for the next succeeding buttonhole.

As above stated, the depending lug g^2 from the under side of the machine supports one end of the belt-driven shaft G' of the stitching mechanism. Said shaft is also supported

toward its rear end in the downwardly-projecting lug g^2 in the bed of the machine. (See Fig. 12^A.)

The stitching-starting shaft B³ is journaled 5 in the upwardly-projecting lugs Q² Q³ in the bed of the machine. (See Fig. 11.)

Those parts of the machine which have not been described above are referred to in connection with the following description of the 10 operation of my machine: The machine when the parts are in positions shown in Figs. 1 to 6, inclusive, is in position for cutting. The operator for inserting the material in which the buttonhole is to be cut and stitched first lifts 15 up the clamping-lever D⁴, thereby allowing spring d⁸ to move the free ends of arms d⁴ to lift upper clamp-jaws D³ above the under clamp-jaws D² for the insertion of the work. The operator now manually moves the clamp-lever 20 D⁴ downwardly, closing the upper jaws D³ on the work. The fabric having been first clamped, the machine is ready to be started. If the fabric has been properly located by the operator in the work-clamp, the lever D⁴ may 25 be thereafter given its second movement required to bring the pawl m⁴ against the upper end of the tripper T, which is adapted to engage and actuate the cutter-starting lever d¹⁹. Tripper T is journaled at t⁷ on the under side 30 of the bed-plate A'. The pawl m⁴ is loosely pivoted at m¹⁰ on the clamp-lever D⁴ and is held with its free end normally forward by a spring m¹¹, Fig. 2. As the operator presses the pawl m⁴ down on the end of the tripper 35 T the tripper is rocked on its pivot t⁷, Figs. 3 and 7, and its free inner end t⁸ (see Figs. 3 and 7) is lifted against the cutter-starting lever d¹⁹, thereby rocking the cutter-starting lever d¹⁹ against the tension of the spring d²³ 40 on its pivot d²² and carrying the incline d²¹ of lever d¹⁹ out of engagement with the head of the driving-pin d¹⁵, which is thereupon forced by its spring d¹⁷ into one of the holes d¹⁶ of the worm-gear b¹⁶. Worm-gear 45 b¹⁶ is preferably provided with a plurality of driving-pin-receiving holes in order that the pin may be received in the worm-gear quicker than would otherwise be the case and to distribute the wear due to repeated interlocking 50 engagement of the driving-pin and continuously-rotated worm-gear, and also to prevent that loss of time which would be occasioned if there were only one or a minimum number of such pin-receiving holes. By the 55 arrangement above described it will be seen that the second manual depression of the clamp-lever D⁴ results in the automatic interlocking of the continuously-driven worm-gear b¹⁶ with the driving-pin carrier d¹⁷, fast on the 60 shaft B³, the continuously-rotating worm b¹⁷ on the stitching-starting shaft B³ causing continuous rotation of the worm-gear b¹⁶. The advantage of this continuously-rotating "prime mover" (as the worm and worm-gear 65 may be called) of the interdependent stitching and cutting mechanisms is that time herefore lost in stopping and starting the ac-

tuating mechanism of this kind of machine is saved. The driving-pin d¹⁵ and worm-gear having been coupled together and the driving-pin being carried by the driving-pin carrier d¹⁴, fast on the stitching-starting shaft B³, the eccentric b⁴ begins to push up the connecting-link b², thereby lifting the rear end and moving down the front end of the upper 70 cutter-lever B². The cutter anvil-bar B' and anvil B are thereby moved down toward the work. During this time the triangular eccentric b⁵ is moved to carry the rear end of the under cutter-lever B⁴ downwardly, and to thereby move the cutter B⁵ upwardly toward the underside of the work and anvil B. Completion of these movements of the anvil and cutter cut the buttonhole-slit in the clamped fabric; but in this cutting operation the 75 upper edge of the cutter does not rise above the upper surface of the under clamping-jaws, and the anvil in the cutting operation presses the work down upon the cutter, so that the latter forms the slit. When the anvil and cutter move apart, the anvil moves away from the work a little quicker than the cutter moves downwardly from the work, and as the cutter has a very slight movement to make to bring its cutting edge below the under surface of the turn-table the turn-table may be moved almost instantly from its cutting position to the stitching position, this movement being about three-eighths of an inch for ordinary buttonholes. 80 Instantly upon the arrival of the clamped fabric at stitching position the stitching instrumentalities begin their operation, the shaft B³ not being arrested until after several 85 stitches have been taken at the small end of the buttonhole and the pulley G² on the under cutting-shaft having been set in operation and being maintained in operation by the rearward end thrust of the shaft-connector f³¹. The worm G on the shaft G' rotates 90 the worm-gear f¹⁷ constantly during the stitching operation, and so during this operation drives the shaft f¹⁶ constantly, whereby the gear f¹⁵, which meshes with the peripheral gear f¹⁴ of the feed-wheel F', is given a constant rotation throughout the stitching of the buttonhole, even when the fabric-penetrating needle h⁵ is through the work. This stitching-feed of the fabric while a needle is through 95 the clamped fabric saves much time heretofore lost in the intermittent feed of the material and is accomplished by giving the upper needles a quick descent and return. The upper needles are so mounted as to move with maximum rapidity during the time one is in 100 the fabric and the other in the buttonhole-slit, and the speed of the continuous feed or turning movement of the turn-table is reduced during the time that the upper needles are in their lowest position. Thus at this 105 time the up-and-down movement of the upper needles is at the maximum speed and the rotation of the turn-table is at its minimum speed. The rotation or turning movement of 110

the turn-table, though continuous, is at a higher rate of speed during the intervals between the formation of the successive stitches than at the times the needle h^5 is in the fabric. This variation in the speed of the rotative movement of the turn-table is accomplished by the novel construction of the worm G, and it is by the combination of the upper needles moving at a high rate of speed when in the fabric with a continuous stitching-feed of the turn-table, which is slowed up at the time the needles are in the fabric, that the high speed of my present machine is due. The novel construction of the worm G is illustrated in Figs. 16 and 3. By reference to Figs. 3, 12, 9, and 16 it will be seen that the shaft G' passes through the eccentric-bushing g, the extension g' of which is mounted in the lug g², depending from and integral with the base-plate A' of the machine. The worm G carries a pin g³, which projects from one of its sides. A block g⁴ is loosely mounted on the projecting portions of said pin and slides in a slot g⁵, cut in the crank g⁶, which is made fast at g⁷ to the shaft G'. The extension g' of the stationary bushing is held in the lug g² by means of suitable fasteners g⁸. The consequence is that when the shaft G' and its fixed crank g⁶ are rotated so as to bring the outer portion of the groove g⁵ in contact with the slide-block g⁴, which is always in fixed relation to the worm G, the block g⁴ and consequently the worm G will be moving at their maximum speed, and at this extreme throw of the crank, as shown in Fig. 16, the high point of the eccentric g' is toward the high effective point of the crank. As the shaft G' continues to rotate the walls of the crank-groove g⁵ and the block g⁴ will change their relative positions, the block traveling toward the longitudinal axis of the shaft G'. As the block g⁴ thus moves in the crank-groove g⁵ nearer to said axis the speed of the worm G is reduced, and as the block g⁴ travels outwardly in said crank-groove g⁵ the speed of the worm G is increased. Shaft G' and shaft f¹⁶ of the worm-gear f¹⁷ are at a fixed distance apart, and consequently the worm and the worm-gear are always in mesh. When the block g⁴ is at the outer end of the crank-groove g⁵, the needles are out of the work and ascending, so that between the times of the penetration of the work by the upper needles the feed of the turn-table is faster than it is when the needles are in the fabric, for at the times when the upper needles are in the fabric the block g⁴ will be nearer to the shaft G', and consequently the worm G will be moving at a reduced speed. The consequence is that in my machine the feed of the fabric is continuous and goes on even when the upper needles are through the fabric, and while it is true that the fabric by this continuous feed is crowded against the cloth-penetrating needle while the other needle is in the fabric, yet the penetrating and rising movement of the fabric-penetrating needle

is made so quick that the seeming antagonism of these movements is reconciled.

I estimate that in making the nine-sixteenths buttonholes, for which the present machine is specifically adapted, and putting in forty-eight stitches into such a buttonhole the turn-table moves a little less than one two-thousandths of an inch while the fabric-penetrating needle is in the fabric. At the completion of the buttonhole the upward movement of the clamp-lever D⁴ brings its pawl O against the shoulder O' on the spreader-lever D⁵, and thereby moves the outer end 80 of the spreader-lever D⁵ inwardly from its spreading position into its non-spreading position preparatory to the beginning of another buttonhole.

In Fig. 29 I show my new buttonhole in which the threads are interlocked in a novel manner, so that the threads are much more durably secured than heretofore. At the small end of the buttonhole the threads are superimposed, the last stitch being in the same hole as the first stitch, so that as the threads are crowded together in the hole through the fabric the same are held tightly in place. This superimposing of the last stitch of the buttonhole upon the first stitch thereof is accomplished in this instance at the time the follower F' falls back into the first recess f¹³ of the hub a', the work-clamp then standing still while the last stitch is being made. The sectional detail included in Fig. 29 is on line x x of the plan, and it will be seen that the upper threads 1 and 2 are superimposed through the fabric 3, as well as through the buttonhole slit or opening 4. The under thread 5 is cut off by the automatic thread-cutter M, and the upper threads 1 and 2 are severed by scissors in the hands of the operator. It will be observed that inasmuch as the threads 1 and 2 are forced through the same hole in the fabric they are therein tightly wedged together. The inner thread represents the thread used in making the first stitch of the buttonhole and the outer thread represents the thread used in making the last stitch of the buttonhole.

Some features of my invention may be used in automatic buttonhole cutting and stitching machines of different well-known types, in some of which the needles are carried around the buttonhole-slit while the fabric is held stationary.

The turn-table in my present machine and the work-clamp, which is movable on the turn-table, as above described, together constitute one form of fabric-holding mechanism. The hereinbefore-described mechanical connection of the under needle or looper with the understitching-shaft and with the spreader so accelerates the coöperation of the under needle and spreader that they work in time with the two upper needles, which have what I call the "quickened" speed when they are in the fabric—that is, when the fabric-penetrating needle is literally in the fabric and the

other upper needle is literally in the button-hole slit. For convenience I herein refer to this position of the two upper needles as the "fabric and slit penetrating" positions.

- 5 In the present machine the work-clamp is reciprocated for the cutting of the button-hole-slit between stitch and cutting positions by means much the same as those employed for the same purpose in my said Patent No. 10 461,498, of October 27, 1891, and at substantially the same rate of speed; but in my present machine the turn-table carrying the work-clamp is turned during the stitching operation at a rate of speed greatly in excess of the 15 rate of speed at which the turn-table is reciprocated for the cutting of the button-hole-slits, the path of the feeding-pin P in the guide-groove f^o (see Fig. 18) being about fifteen inches, and the gears and pulleys of the machine being so arranged that the turning speed of the turn-table throughout the stitching of a buttonhole is very greatly in excess of the reciprocatory speed of the turn-table. The quick thrust and return of the upper 20 needles to and away from their lowermost or fabric-penetrating position in connection with this high-speed turning of the turn-table during the stitching of a buttonhole and relatively low speed of the reciprocation of the 25 turn-table for the cutting of a buttonhole-slit between the times of stitching two buttonholes in succession results in making a very high-speed machine.

The quick end thrust of the two upper needles, one into the fabric and the other into the buttonhole-slit, and the quick return of said needles from this position are accomplished 30 by mounting the needle-bar h^o with its lengthwise axis at one side of the lengthwise axis of the needle-bar shaft II in a manner too well 35 known to require further description.

What I claim is—

1. In an automatic buttonhole cutting and stitching machine, the combination of a buttonhole-cutting mechanism; a buttonhole-stitching mechanism comprising a pair of upper needles; a turn-table carrying a work-clamp; a work-clamp; means for reciprocating the work-clamp between stitching and cutting positions; and means for turning the turn-table, during the stitching operation, at a rate of speed in excess of the speed at which the work-clamp is reciprocated; and means for giving the two upper needles a quickened 45 thrust into and a quickened return from their fabric and buttonhole-slit penetrating position.

2. In an automatic buttonhole cutting and stitching machine, the combination of a buttonhole-cutting mechanism; a buttonhole-stitching mechanism; a fabric-holding mechanism; the fabric-holding mechanism and the stitching mechanism being movable one in relation to the other, for the stitching of a buttonhole-slit; a shaft having a worm; a shaft having a worm-gear with which said worm meshes, said worm being eccentrically

mounted on its shaft and provided with a projection which enters a lengthwise groove in a radial arm fixed on said shaft; said radial 70 arm having said lengthwise groove; and means which connect the said worm-gear with the fabric-holding mechanism.

3. In an automatic buttonhole cutting and stitching machine, the combination of a frame provided with a throat-plate; a cutting mechanism; a stitch-forming mechanism comprising a pair of upper needles; a work-clamp; feeding and spacing mechanism; an actuating mechanism for the said feeding and spacing mechanism, and devices to automatically control the effective speed of the stitching, feeding and spacing mechanism during the stitching of a buttonhole, and after the cutting mechanism is put into and removed 85 from position with relation to the work-clamp, or between the times of operating the buttonhole-cutting mechanism for the cutting of two buttonholes in succession; and means for giving two upper needles of the said 90 stitching mechanism a quickened thrust into and return from their fabric and buttonhole-slit penetrating position.

4. In an automatic buttonhole cutting and stitching machine, the combination of a cutting mechanism; a stitching mechanism comprising a pair of upper needles; and means for accelerating the speed of said needles during the time they are in the fabric and buttonhole-slit; with a turn-table and work-clamp carried thereby; means for operating the cutting mechanism; and means for continuously turning said turn-table at a varying speed, during the stitching operation, the lesser speed thereof being while said needles are in 105 the fabric and the buttonhole-slit.

5. In an automatic buttonhole cutting and stitching machine, the combination of a buttonhole-cutting mechanism; a buttonhole-stitching mechanism; a fabric-holding mechanism; the fabric-holding mechanism and the stitching mechanism being movable one in relation to the other, for the stitching of a buttonhole-slit; means for actuating the buttonhole-cutting mechanism; means for actuating the buttonhole-stitching mechanism; said stitching mechanism comprising a pair of upper needles and an under needle or looper; an interlacer having a lengthwise and oscillating movement in relation to said upper needles; and means which gives the interlacer its lengthwise and oscillating movements.

6. In an automatic buttonhole cutting and stitching machine, the combination of a buttonhole-cutting mechanism; means for operating it; a buttonhole-stitching mechanism; means for operating it; a fabric-holding mechanism, said fabric-holding mechanism and stitching mechanism being movable one in 125 relation to the other for the stitching of a buttonhole-slit; said stitching mechanism comprising a pair of upper needles; a needle-bar carrying said upper needles; a pair of

- lateral projections from the upper portion of the needle-bar, one projection being for one upper thread, and the other projection being for the other upper thread; the projection for the thread that passes through the fabric-penetrating needle being higher on the needle-bar than the other projection which supports the thread that passes through the buttonhole-slit-penetrating needle; a pair of thread-tension devices, one for each upper thread; and a stationary bracket having a pair of pivoted thread-pressing arms, one for each of said upper threads, the projection which supports the thread for the fabric-penetrating needle, 5 in its upward movement engaging that thread before the projection which supports the thread for the slit-penetrating needle engages its thread, and thereby providing the fabric-penetrating needle with the excess length of 10 thread which it requires, over that required by the slit-penetrating needle, for the formation of each stitch.
7. In an automatic buttonhole cutting and stitching machine, the combination of a buttonhole-cutting mechanism, comprising a co-operating cutter and anvil, each operated by levers journaled on the stationary part of a machine; said levers; a buttonhole-stitching mechanism comprising a belt-driven shaft 15 and a pair of upper needles, one of which penetrates the work, and the other of which passes through the buttonhole-slit therein, said needles being carried by a needle-bar mounted on the stationary gooseneck of the machine; an under needle or looper; a turn-table and a movable work-clamp mounted thereon; a mechanism connecting the under cutter-lever with the turn-table to reciprocate it between cutting and stitching positions; 20 means for turning the turn-table continuously during the stitching operation; means for giving the upper needles a quickened rate of movement into and out of their fabric and buttonhole-slit penetrating positions; means 25 for reducing the speed of the turning movement of the turn-table at the times the upper needles are in their fabric and slit penetrating positions; a stitching-starting shaft; means for operatively connecting said shaft 30 with the cutting mechanism and with the upper and under cutter-levers; means for connecting the under cutter-lever with said turn-table to reciprocate it between cutting and stitching positions; a loose-running pulley 35 contiguous to a belt-driven pulley of the stitching mechanism; an automatic belt-shipper for moving a belt from said loose-running pulley upon the belt-driven pulley of the stitching mechanism; a gear loose on said 40 stitching-starting shaft; means for coupling said gear to compel it to rotate with said stitching-starting shaft; a continuously-rotating prime mover for said gear on the stitching-starting shaft; a connector mounted on 45 and operated by an eccentric on the stitching-starting shaft and engaging said belt-shipper to ship the belt from the loose to the

driven pulley of the stitching-shaft, or while the cutter and anvil are moving away from their co-operating positions, and so stitch a portion of the buttonhole before the cutting mechanism reaches its position of rest; said connector for the stitching-starting shaft and for the belt-driven shaft of the stitching mechanism remaining in engagement with the belt-shipper throughout the stitching operation, whereby the stitching-starting shaft maintains the stitching mechanism in stitching position throughout the stitching operation; means for automatically moving said belt-shipper to ship the belt from the driven to the loose pulley, said connector being disengaged from the belt-shipper at the completion of the stitching of a buttonhole; means carried by the stitching-starting shaft for automatically disengaging said connector from the belt-shipper; means for automatically clamping the work without starting the machine; means for starting the machine through a depression of the work-clamp lever; and means for automatically stopping the machine at the completion of each buttonhole; all combined and operating so that the speed at which the turn-table is turned during the stitching operation is variable but continuous.

8. In a buttonhole-stitching machine, the combination with buttonhole-cutting devices, a stitching mechanism, and starting devices for said stitching mechanism, of a common cutter-operating and stitching-starting shaft, means for rotating said shaft and for arresting its motion, and mechanism whereby when said shaft is started the cutting devices will first be operated to cut a buttonhole and the stitching mechanism will subsequently be set in motion and one or more complete stitches be formed after the buttonhole has been cut and before the complete rotation of said shaft is effected to return the cutting devices to their initial positions; whereby time is saved in stitching a buttonhole.

9. In a buttonhole-stitching machine, the combination with buttonhole cutting and stitching mechanisms, of a turn-table or clamp base-plate, work clamping and spreading devices carried by said turn-table or base-plate mechanism for reciprocating said turn-table between cutting and stitching positions, means for imparting traveling movements, lengthwise of the buttonholes, to said turn-table, means for imparting periodical turning movements to said turn-table, a clamping-lever by the depression of which the adjusted work is first clamped, without starting the machine, and a starting-lever arranged to be engaged by a device on or part of said clamping-lever when said last-named lever has been given a second or additional movement after the work has been clamped.

10. In an automatic buttonhole cutting and stitching machine, the combination of co-operating cutting and stitching mechanisms, with a work-clamp; a turn-table conveying

the work-clamp; a feed-wheel having a recess in its under side; and a pivotally-mounted cutter-starting lever, the feed-wheel holding the cutter-starting lever in inoperative position during the stitching operation, means for actuating the feed-wheel; and means for enabling the feed-wheel to hold the cutter-starting lever in inoperative position.

11. In a buttonhole-stitching machine, the combination with a buttonhole-cutting mechanism and feeding devices to space the stitches, of work-holding means, a stitching mechanism comprising one or more needles above the work-support and a thread-carrying looper below the work-support, a horizontally-swinging lever also located beneath the work-support and provided with a thread-cutter arranged to sever the looper-thread, and automatic means for actuating said lever to cause it to cut the looper-thread at the completion of the stitching of each buttonhole.

12. In an automatic buttonhole cutting and stitching machine, the combination of a buttonhole-cutting mechanism; a buttonhole-stitching mechanism and a work-clamp, the work-clamp and buttonhole-stitching mechanisms being movable one in relation to the other; said cutting mechanism comprising an under cutter-lever and an upper cutter-lever; a stitching-starting shaft having a triangular eccentric for operating the under cutter-lever, and having an eccentric for operating the upper cutter-lever, said levers being pivoted to the frame of the machine; and means for operating said stitching-starting shaft.

13. In an automatic buttonhole cutting and stitching machine, the combination of a buttonhole-cutting mechanism; a buttonhole-stitching mechanism; a work-clamp, said clamp and stitching mechanism being movable one in relation to the other, for the stitching of a buttonhole; said cutting mechanism comprising an upper cutter-lever and an under cutter-lever, each of said levers being pivoted to the frame of the machine; a stitching-starting shaft; means for operating the upper and under cutter-levers from said shaft; a worm-gear on said shaft; and a continuously-rotated worm-shaft which operates said worm-gear; means for compelling said worm-gear to rotate with said shaft; said stitching mechanism comprising a power-driven shaft; and means for connecting the stitching-starting shaft with said stitching-shaft during the stitching operation.

14. In an automatic buttonhole cutting and stitching machine, the combination with a stitch-forming mechanism, of a turn-table or clamp base-plate provided with two pairs of clamping-jaws and a jaw-spreading mechanism comprising a spreading-lever, means for turning said turn-table or clamp base-plate during the stitching operation, a latch-pin frame projecting from the work-clamp, a rocking lever, and a latch-pin movably mounted in the upper end of said rocking lever and en-

gaging with said latch-pin frame, said rocking lever having an incline in the path of said spreading-lever whereby the latter is moved to spread the clamping-jaws at the proper time.

15. In an automatic buttonhole cutting and stitching machine, the combination of a turn-table; a work-clamp movable thereon; a latch-pin frame rigid with the work-clamp and formed at its outer end with a slot to receive the latch-pin; a latch-pin; a swinging lever in which the latch-pin is mounted movably; said lever having a cross-groove through which the outer end of the latch-pin frame moves when disengaged from said latch-pin; a projection on the latch-pin; and a latch-pin-releasing lever with which said projection engages to disengage the latch-pin from the latch-pin frame.

16. In an automatic buttonhole cutting and stitching machine, the combination of buttonhole cutting and stitching instrumentalities organized and mounted in a frame, and comprising a stitching-starting shaft common to both the cutting and stitching instrumentalities, with a supporting-bracket for said frame, which is pivoted on said bracket; an automatically-actuated belt-shipper journaled on said bracket; a loose pulley journaled on said bracket; means for automatically swinging the belt-shipper into operating position with said loose pulley; said frame and thereby-supported instrumentalities comprising an understitching-shaft having a fixed pulley, the journals of said loose and fixed pulleys being normally in line, one with the other, and a connector carried and operated by said stitching-starting shaft, the connector automatically engaging said belt-shipper to move the belt from the loose to the fixed pulley, and to hold it there throughout the stitching operation.

17. In an automatic buttonhole cutting and stitching machine, the combination of a buttonhole-cutting mechanism; a buttonhole-stitching mechanism; a turn-table; a work-clamp carried thereby; means for reciprocating the work-clamp between stitching and cutting positions on said turn-table; a feeding-pin through the work-clamp; a cam feed-wheel; a guideway for the feeding-pin, intermediate said turn-table and said cam-wheel; the cam feed-wheel being provided with peripheral teeth, and also with a groove which receives the feed-pin, said groove being provided with followers substantially as described; and means for rotating said feed cam-wheel at a variable speed in the making of each stitch.

18. In an automatic buttonhole cutting and stitching machine, the combination of a buttonhole-cutting mechanism; a buttonhole-stitching mechanism; a work-clamp, the work-clamp and the buttonhole-stitching mechanism being movable, one in relation to the other, for effecting the stitching of a buttonhole; a tripping-lever pivoted to the frame of

the machine, with its upper end projecting through the frame of the machine near the work-clamp, and its inner end in position to engage the cutter-starting lever; the cutter-starting lever having a cam-shaped end; a stitching-starting shaft having a driving-pin carrier fastened upon it; a loose gear on said shaft provided with recesses to receive the driving-pin; the cam-shaped end of the cutter-starting lever coöperating with said driving-pin, and means for operatively connecting the stitching-starting shaft with the cutting mechanism to actuate the same; said work-clamp having a lever provided with a pawl which is adapted to engage the upper end of said tripping-lever.

19. In an automatic buttonhole cutting and stitching machine, the combination of a buttonhole-cutting mechanism comprising an undercutter-lever; a buttonhole-stitching mechanism; a fabric-clamping mechanism, said clamping mechanism and stitching mechanism being movable one in relation to the other; a thread-cutter pivoted on the frame 25 of the machine; and in the path of the under cutter-lever and engaged thereby to move it back out of cutting position; a tripping-lever pivoted on the bed of the machine and projecting into the path of the cutter to lock it 30 in inoperative position.

20. In a buttonhole-stitching machine, the combination with a stitch-forming mechanism, of a buttonhole-cutting mechanism comprising an under cutter-lever, work holding and feeding devices, a stop-lever, as F^3 , having a portion, as arm f^{21} , in position to be engaged at times by a portion, as f^{26} , of said under cutter-lever, and said under cutter-lever having a part or shoulder, as f^{28} , a stop-motion mechanism connected with said stop-lever, a transverse rocker-bar, as F^4 , having a surface or portion, as f^{27} , arranged to be engaged at times by said part or shoulder f^{28} on said under cutter-lever, and said rocker-bar having a part, as lug f^{28X} , said work-feeding devices comprising a worm feed-gear, as f^1 , having a part, as lug f^{29} , to be engaged at times by said lug f^{28X} , when the rotation of said worm feed-gear is to be suspended; 45 whereby the said stop-lever may be moved to an inoperative position, at times, and subsequently be released to actuate the stop-motion mechanism.

21. In an automatic buttonhole cutting and stitching machine, the combination with buttonhole cutting, stitching and fabric-clamping mechanisms, and means for changing the relative positions of said stitching and fabric-clamping mechanisms, said buttonhole-stitching mechanism comprising a pair of upper needles and an under-thread-carrying looper, of an automatic under-thread cutter, and a movable thread-pull-off device which pulls off underthread in the making of the last buttonhole-stitch, in order to supply thread for the under needle when the under thread is cut, the said pull-off device being operated before the

thread-cutter is operated, means for holding the pull-off device inoperative during the stitching of the buttonhole up to the completion of the last stitch, means for holding the cutter inoperative during the stitching of the buttonhole, means for actuating the under-thread cutter; and means for oscillating the under-thread pull-off device. 70

22. In an automatic buttonhole cutting and stitching machine, the combination of a buttonhole-cutting mechanism; a buttonhole-stitching mechanism; with a clamping mechanism, the buttonhole-stitching mechanism 80 and the work-clamping mechanism being movable one in relation to the other for the stitching of the buttonhole-slit, a rocker-bar journaled on a stationary part of the machine; a three-armed stop-lever pivotally mounted 85 in the machine; means for moving said stop-lever, one arm of the stop-lever being adapted to engage the rocker-bar; another arm of the stop-lever being in the path of the under cutter-lever, which is comprised in the buttonhole-cutting mechanism; and another arm of 90 said stop-lever being in the path of a three-armed rocker-lever; a three-armed rocker-lever; a stitching-starting shaft which supports said three-armed rocker-lever, one arm of said 95 three-armed rocker-lever coöperating with a shaft-connector; a shaft-connector mounted on said stitching-starting shaft; means connecting the stitching-starting shaft with the buttonhole-cutting mechanism; a belt-shipper engaged by said shaft-connector; an understitching-shaft for said stitching mechanism; said three-armed rocker-lever comprising an upwardly-extending arm; a thread-releasing lever pivotally mounted in the machine 100 with its rear end in position for engagement with said upwardly-extending arm of the three-armed rocker-lever; a hook on said thread-releasing lever in the path of the upper cutter-lever comprised in said cutting 105 mechanism. 110

23. In an automatic buttonhole cutting and stitching machine, the combination of a buttonhole-cutting mechanism; a buttonhole-stitching mechanism; a work-clamping mechanism, the work-clamping mechanism and the buttonhole-stitching mechanism being movable one in relation to the other for the stitching of a buttonhole; an automatic thread-cutter; a tripping-lever pivoted on the 115 bed of the machine with its upper end projecting through and above the bed of the machine, said work-clamp having a lever provided with a pawl which engages with the upper end of said tripping-lever when the work-clamp lever is lifted. 120

24. In an automatic buttonhole cutting and stitching machine, the combination of a buttonhole-cutting mechanism; a buttonhole-stitching mechanism; a fabric-clamping mechanism, the buttonhole-stitching mechanism; a fabric-clamping mechanism and the fabric-clamping mechanism being movable one in relation to the other for the stitching of a buttonhole; and the fabric- 130

clamping members comprising a clamp-lever having a pawl; means for reciprocating the work-clamp between cutting and stitching positions; a tripper pivoted in the machine, with one end projecting up through the bed of the machine unto the path of said pawl; a cutter-starting lever engaged by said tripper; and mechanism for actuating the cutting mechanism; the said pawl being carried out of engagement with said tripper when the work-clamp is moved from stitching into cutting position.

25. In an automatic buttonhole cutting and stitching machine, the combination of a buttonhole - cutting mechanism; a buttonhole-stitching mechanism; a fabric-holding mechanism; said stitching mechanism and holding mechanism being movable one in relation to the other; said stitching mechanism comprising a pair of upper needles; means for giving said upper needles a quickened thrust into and return from their fabric and slit penetrating positions; said stitching mechanism also comprising an understitching-shaft; an under needle or looper; a spreader in proximity to the under needle and in coöperative relation therewith; a link connection between the understitching-shaft

and the looper, and spreader being provided with a cam-roll which enters a groove in a cam carried by said understitching-shaft.

26. In an automatic buttonhole cutting and stitching machine, the combination of a buttonhole - cutting mechanism; a buttonhole-stitching mechanism; a fabric-holding mechanism; means for continuously rotating the fabric-holding mechanism during the stitching operation; means for reducing the speed at which said holding mechanism travels at the time the upper needles are in their fabric and slit penetrating positions; said stitching mechanism comprising a pair of upper needles; an under needle; and a spreader; means for giving the upper needles a quickened thrust into and return from their fabric and slit penetrating positions; and means for accelerating the coöperating movements of the under needle and spreader at the time the upper needles are in their said fabric and slit penetrating positions.

In testimony whereof I affix my signature in presence of two witnesses.

JOHN W. LUFKIN.
